UNITED STATES PATENT OFFICE

98,125

DESIGN FOR A TANK VEHICLE

Frederick G. Thwaits, Wauwatosa, Wis., assignor
to The Heil Co., Milwaukee, Wis., a corporation
of Wisconsin

Application November 16, 1934, Serial No. 54,041

Term of patent 14 years

To all whom it may concern:

Be it known that I, Frederick G. Thwaits, a citizen of the United States, residing at Wauwatosa, in the county of Milwaukee and State of Wisconsin, have invented a new, original, and ornamental Design for a Tank Vehicle, of which the following is a description, reference being had to the accompanying drawing, forming part thereof.

In the drawing:

Fig. 1 is a side elevation of a complete tank vehicle embodying my new tank vehicle design;

Fig. 2 is a full top view of the vehicle tank; and

Fig. 3 is a rear view of the tank vehicle.

The important features of my present new

design are shown in solid lines, and comprise the formation of the top portion of the tank with an open elongated central trough within which the manhole covers are disposed and which has straight side walls of sufficient height to conceal the covers when the vehicle is viewed from the sides and end, and also the reversely curved upper and lower rear transverse portions connected by a downwardly and rearwardly inclined and continuously laterally curved rear wall; and the immaterial features of my present design are shown in dot-and-dash lines.

I claim:

The ornamental design for a tank vehicle, substantially as shown and described.

FREDERICK D. THWAITS.
